UNITED STATES PATENT OFFICE.

LILYAN M. ELLIOTT, OF SAN DIEGO, CALIFORNIA.

BOTTLE HOLDER.

Application filed June 21, 1923. Serial No. 646,938.

To all whom it may concern:

Be it known that I, LILYAN M. ELLIOTT, a citizen of the United States, residing at San Diego, in the county of San Diego and 5 State of California, have invented certain new and useful Improvements in Bottle Holders, of which the following is a specification.

This invention relates in particular to 10 nursing bottle holders adapted to be fastened around the neck of a nursing bottle and provided with suitable means for attaching same to a crib or other object.

The principal object of my invention is 15 to provide a simple device for attaching a nursing bottle to a crib.

Another object is to provide a ring having an easily adjustable clamp for attaching to the neck of a nursing or other bottles 20 of various sizes, the said ring being provided with a cord or chain and other rings for attaching same to the bar of a crib or to some part of an infant's high chair or baby carriage to prevent the bottle from being 25 thrown to the floor or ground and broken.

Another object is to provide an easily adjustable hinged clamp in connection with a flexible ring, having a semi-hard rubber or cork lining, said ring having a notched and 30 grooved tongue at its other end adapted to fit into the hollow hinged member and be clamped down tight by a set screw having preferably a milled edge.

Another object is to provide a ring, having 35 a chain attached thereto, adapted to be attached to any type of bottle to prevent it from being dislodged from its normal resting place and being thrown to the floor or ground and broken.

40 The matter constituting my invention will be defined in the claims.

I will now describe my invention in detail by reference to the accompanying drawings, in which:

45 Figure 1 represents an elevation of a nursing bottle holder showing the hollow hinged locking member partly in cross section, and a chain attached thereto.

Fig. 2 represents a view of the outer periphery of the hollow hinged locking member showing method of attaching to one end of the ring.

50 Fig. 3 is a transverse section of the ring on the line 3—3 of Fig. 1.

55 Fig. 4 is an end view of the opening in the free end of the hinged locking member.

Fig. 5 is a view of the inner periphery of the hinged locking member showing method of attaching to the ring and a portion of the notched tongue of the ring inserted 60 therein.

The flexible and adjustable bottle holder A, is composed of the open metal ring portion B, having an interior groove B', and a resilient rubber or cork ring C inserted in 65 said groove B' and extending from the point X to the point X'. The ring B is provided at one end with a tongue D, having a plurality of grooves E and notches E' on its inner periphery, said tongue being adapted 70 to fit into the free and open end of the hollow locking member F which is attached to the other end of the open ring B at the point G by a rivet or pin H. The hollow hinged locking member F is provided at the 75 opening L with a bar M to form a square opening and for another purpose herein-after described, the remainder of the hinged member being open on the inner periphery and closed on the sides and outer periphery, 80 except at the point G where the outer periphery is cut away slightly to permit of a free movement on the rivet H which passes through the sides of the member F at one end and the end of the ring B, which fits 85 therein, thereby forming a hinge. The hollow member F is provided at the point I with a set-screw K, having preferably a milled edge. The ring B is also provided with a small ring N at the point N' and to 90 the ring N is attached a cord or chain O provided with a small ring O', to which is attached a cord or chain P provided with a snap ring P' to be fastened to the ring O'.

My invention is adapted primarily to be 95 attached to a nursing bottle and also to some portion of a crib, infant's high chair, baby carriage or other object, to prevent the bottle from being thrown to the floor and broken, but I wish it to be understood that I do not 100 limit my invention to this particular purpose, for the ring itself can be made in various sizes and adjustably fastened to larger bottles or jars, for example, it may be attached to a milk bottle which is placed on 105 a window ledge and the chain or cord attached to a fixed hook, eye-screw or other object within the window opening, so that the bottle will not be carelessly knocked to the ground and broken.

The ring B being flexible and also provided with the hollow hinged locking mem-

ber F and the notched tongue D, permits it to be easily adjusted to nursing or other bottles having necks of slightly varying sizes. This novel adjustable ring clamp will be 5 made in standard sizes and the adjustable feature of each size will permit it to be used on varying sized bottle necks. The tongue D, at one end of the ring portion B, is provided with a plurality of grooves and notches 10 E on the inner periphery. This tongue is inserted in the opening L of the member F and adjusted by means of the grooves E fitting over the bar M on the inner periphery of the said member F, so that the bar M 15 rests between two of the notches E'. When the tongue is properly adjusted the set screw K, which is positioned in the outer periphery of the member F, is screwed down tight against the outer periphery of the 20 tongue D to hold it in place and thereby prevent the ring from slipping off of the neck of the bottle.

The ring B is provided with an annular groove B' within its inner periphery and in 25 this groove is inserted a ring C of medium hard rubber or cork, extending from the point X to the point X' to prevent the metal ring from slipping or coming into contact with the neck of the bottle.

30 The chain or cord O, which is attached to the ring B by means of the ring N at the point N', is provided at its other end with a ring O' to which is attached another cord or chain P having a snap ring P' attached 35 thereto, said chain P being employed to fasten around some object such as a crib bar or crib rail and the snap ring P' attached to the ring O'. This chain may be short or long according to the distance from the place 40 where it is attached to the floor. Of course the chain will be of such a length as to permit the use of the bottle.

Having described my invention, what I 45 claim and desire to secure by Letters Patent, is:

1. A circular member of metal or other flexible material lined with rubber or cork, a hollow locking member hinged to one end of said circular member and having a bar 50 on its inner periphery and a tongue having

a plurality of transverse grooves and notches, fixed to and forming a part of or continuation of said circular ring member, adapted to fit into the hollow locking member and be locked in position by a thumb screw positioned on the outer periphery of the said hollow locking member substantially 55 opposite said bar.

2. A hollow locking member riveted at one end to one end of a flexible ring member, forming a hinge, said locking member having a set screw fitted into the outer periphery of its opposite end, said ring member having a tongue provided with a plurality of grooves and notches and adapted 60 to be inserted in the open and free end of said locking member, said locking member having a bar connecting its sides at its inner periphery, said bar being adapted to fit into the grooves and between the notches 65 within the inner periphery of said tongue and said set screw adapted to be screwed against the outer periphery of said tongue to hold it in place against the bar in the free and open end of the said locking member to hold the ring securely in place around 70 the neck of a bottle.

3. In combination with an annular metal member, having a lining of suitable material to form a cushion, a hollow locking member 75 fixed to one end and a grooved and notched tongue fixed to and forming a part of the other end of said annular member, said tongue being adapted to be inserted in one end of the hollow locking member and be 80 fixed in place by means of a bar extending across the open end of the hollow locking member and a thumb or set screw positioned in the outer periphery of said locking member, said annular member being adapted to 85 be attached to the neck of a bottle or jar or any other object to which it may be adapted, and having fixed to it a chain or cord, said 90 cord or chain being provided at its other end with a plain ring, a relatively short chain or cord, and a snap ring for attaching same to some other object.

In testimony whereof I affix my signature.

LILYAN M. ELLIOTT.
